UNITED STATES PATENT OFFICE.

OZIE F. FREEMAN, OF STOCKTON, ALABAMA.

ARTICLE OF MANUFACTURE.

Application filed August 20, 1926. Serial No. 130,513.

This invention contemplates the provision of a new article of manufacture having an unlimited number of uses, such as a roofing shingle, tiling and novelties, the invention residing in the construction and combination as claimed.

In the drawing forming part of this application like numerals of reference indicate similar parts in the several views and where-

10 in:

Figure 1 is a front elevation.

Figure 2 is a sectional view on line 2--2 of Figure 1.

Referring to the drawing in detail 10 indicates the base of the article, which may be constructed of any suitable material, and also vary in size and configuration without departing from the spirit of the invention. This base is provided with a facing, which 20 as illustrated is composed of fish scales 11, such as the scales taken from garfish. These scales are preferably arranged in overlapping relation as clearly illustrated in the drawing. The scales may be secured to a 25 backing and the latter attached to the base 10, or the scales may be cemented or otherwise directly attached to the base 10 as indicated at 12.

While it is believed that from the foregoing description, the nature and advantages 30 of the invention will be readily apparent, I desire to have it understood, that I do not limit myself to what is herein shown and described and that such changes may be 35 resorted to when desired as fall within the scope of what is claimed.

What is claimed is:

As a new article of manufacture, a base, 40 garfish scales covering one side of the base, said scales being substantially of uniform dimensions and having their opposed edges slightly tapered, with the adjacent edges of the various scales arranged in overlapping relation, a sheet of material to which the 45 scales are attached, and means for securing the sheet of material to the side of the base.

In testimony whereof I affix my signature.

OZIE F. FREEMAN.
